(57) **CLAIM**

We claim the ornamental design for insect pest control delivery device, as shown and described.

DESCRIPTION

FIG. 1 is a front elevation view of an insect pest control delivery device showing our new design;
FIG. 2 is a rear elevation view thereof;
FIG. 3 is a top plan view thereof;
FIG. 4 is a bottom plan view thereof;
FIG. 5 is a right side elevation view thereof;
FIG. 6 is a left side elevation view thereof;
FIG. 7 is a perspective view thereof;
FIG. 8 is a front elevation view thereof, shown in a folded position of use;
FIG. 9 is a top plan view thereof, shown in a folded position of use;
FIG. 10 is a cross-sectional top plan view thereof, taken along line A-A in FIG. 1; and,
FIG. 11 is a perspective view thereof; shown in a folded position of use.
The portion of a plant or tree shown in FIG. 11 is directed to unclaimed environment. The broken lines form no part of the claimed design.
